WINDING SPOOL.

Filed Nov. 7, 1930

UNITED STATES PATENT OFFICE

CHARLES K. DUNLAP, OF HARTSVILLE, SOUTH CAROLINA, ASSIGNOR TO SONOCO PRODUCTS COMPANY, OF HARTSVILLE, SOUTH CAROLINA, A CORPORATION OF SOUTH CAROLINA

WINDING SPOOL

Application filed November 7, 1930. Serial No. 494,111.

This invention relates to spools, bobbins, or the like, and to apparatus for assembling the same; and it has for its objects the provision of an improved spool or bobbin for 5 thread, wire, or similar material, the end discs of which are secured to the body members thereof by means of novel fastening elements, and also the provision of novel apparatus for applying these fastening elements to the 10 spool.

More particularly, it is an object of the present invention to provide novel securing elements for attaching the end discs or flanges of a spool to the body portion, which involve 15 the features of ease and economy of manufacture, simplicity of construction, and rigidity and durability of the resulting assembled spool.

The invention further contemplates the 20 provision of a practical device for applying the securing elements to the body member and end discs of a spool, in which device there are employed a minimum number of simple parts, and which is susceptible of operation 25 by hand, foot or mechanical power.

Other objects and features of novelty will 30 be apparent from the following specification when read in connection with the accompanying drawing in which certain embodiments of the invention are illustrated by way of example.

In the drawing,

Figure 1 is a vertical sectional view of one 35 embodiment of the novel spool construction and apparatus for assembling the same; the upper securing element being in final assembled position and the lower one shown in process of being applied;

Figure 2 is a fragmentary plan view of one 40 end of the spool;

Figure 3 is a perspective view of one of the 45 securing elements in contracted position prior to being applied to the spool;

Figure 4 is a fragmentary vertical sectional view of one end of a spool in which a modified 50 form of securing means is employed;

Figure 5 is a side elevational view of one 55 of the securing elements shown in Figure 4; and

Figure 6 is an end view of the same element.

The spool, designated generally in the drawing by the numeral 10, is provided with a preferably cylindrical core or body member 11 which may be tubular with a bore 12, as shown, or which may be solid and provided with openings or recesses in the ends thereof. End discs 13, which are provided with central apertures 14 adapted to register with the ends of the bore 12, are secured to each end of the body member 11 by means of the novel securing elements which will presently be described.

In order to avoid the insecure or expensive means of fastening these end discs and flanges to the cores of the spools, such as by the use of nails or other more complicated fastening devices, there has been devised the simple annular or parti-annular securing elements which form an important feature of the present invention. In the modification 70 illustrated in Figures 1-3, inclusive, of the drawing, the securing element is designated by the numeral 15 and is seen to be in the form of a ring the ends of which, in contracted position, are adapted to overlap as at 16 (Fig. 3). These elements are preferably formed of flat strips of metal having their margins flared radially outwardly as at 17 and 18.

In applying these elements to the spool, the end disc 13 is positioned with respect to the body member 11 so that the aperture 14 of the end disc registers with the central bore or opening 12 of the body member. The securing element 15 is inserted in the opening so that substantially all of the element except one of the flanges is disposed within the opening 12 and aperture 14. The element 15 is then designed to be expanded 80 so that the inner flange 18 is embedded in the inner wall of the body member. The outer flange 17 is adapted to overlie the margin of the aperture 14 in the end disc 13 and to securely retain the disc in position. The flange 17, if desired, may be made somewhat wider than the inner flange 18, the last named flange being designed to penetrate but a short distance into the material forming the body member of the spool.

The circumference of the member 15 is 100

predetermined with reference to the dimensions of the bore 12 and aperture 14 so that when the securing element is expanded into its final position in the end of the spool, the overlapping ends will move into abutting position as indicated at 20 in Figures 1 and 2. This will effectively prevent dislodgment of the fastening element and it will be readily seen that the device may be applied to a spool without expanding or distorting the head thereof. It will also be perceived that the element 15 functions not only as a securing means for the assembled parts of the spool but also as a means for reinforcing both the body member 11 and the end disc or flange 13.

In Figure 1, there is illustrated a simple and effective mechanism for applying the fastening element 16 to a spool, reel, bobbin, or similar device, as described. The operation and construction of this mechanism will be readily understood. The mechanism consists essentially of a block 22 which is disposed upon the bench, table or other support 23 and is provided with the central aperture 24 having tapered walls, the purpose of which will be apparent as the description proceeds. Disposed within the aperture 24 is a preferably cylindrical sleeve 25 which is split from the upper end thereof to a point near the lower end at spaced intervals around the circumference thereof as shown at 26. This gives to the sleeve 25 the conformation of an annular base portion 27 from which extend upwardly peripherally spaced strips or fingers 28. Within the sleeve 25 there is adapted to slidably reciprocate the plunger 30 which is adapted to pass also through the opening 31 in the table 23. Upon the upper end of the plunger 30 there is formed a tapered portion 32 which, in the present case, takes the form of the frustum of a cone. The piston 30 may be reciprocated by any convenient means, a preferred means being indicated in Figure 1 and comprising the lever or pedal 35 which is fulcrumed as at 36 upon the fixed bracket 37 and is pivoted to the lower end of the plunger 30 as by means of the pin and slot connection 38.

In applying one of the securing elements 15 to the end of a spool, the various parts are disposed as indicated in Figure 1, with the element 15, end disc 13 and body member 11 disposed around the expander sleeve 25 and supported by the block 22. It will be readily seen that by depressing the pedal 35, the tapered head 32 of the plunger 30 will be drawn downwardly within the expander sleeve 25, thus forcing the fingers or furcations 28 radially outwardly. This will, of course, expand the member 15 until the ends thereof move into abutting position as at 20 and the flange 18 is firmly embedded in the walls of the opening 12. Upon release of pressure from the pedal or lever 35 the plunger

30 will be returned to its initial position by any suitable means, such as the spring 40. The spool may then be removed from the device and the opposite end thereof assembled in the same way.

No further securing means is necessary than that which has just been described but, of course, a bushing of any suitable size or material may be inserted in the ends of the completed spool for the purpose of providing bearing means for an axle which may be inserted therein.

An alternative modification of the securing element is illustrated in Figures 4-6, inclusive. In this modification, one or more securing elements 15' may be employed, these elements being formed of curved strips provided with flanges 17' and 18' and being of arcuate shape of any preferred extent less than 360°. In the form illustrated, two of the fastening elements 15' are employed, each being somewhat less than semi-circular. The inner flanges 18' are adapted to be embedded in the walls of the opening 12 in the body member 11 and the outer flanges 17' are adapted to overlap the margins of the aperture 14 in the end disc 13, as in the example first described. In this form, however, it is preferred that a bushing 41 be employed both for the purpose of providing axle bearing means and for retaining the securing elements 15' in position. The elements 15' may be applied by means of the device illustrated in Figure 1, as in the case of the first embodiment, or they may be expanded by employing a bushing 41 which is formed with a taper 42 upon its inner end and thus forcing the elements 15' radially outwardly during the progress of the bushing into the opening 12.

The body member 11 is formed of any rigid material into which the flanges 18 or 18' may be embedded, such as pasteboard, fiber, soft wood or a similar substance. The end discs 13 may be of the same material or may be constructed of metal, if desired. Bushings 41, although preferably made of wood, may be constructed of pasteboard, fiber, metal or any suitable material.

It will be seen that there has been provided, by means of the present invention, a novel and eminently practical securing element for spools, reels, bobbins, or the like, and one, the use of which, will effect great economies in the production of such winding elements as have been mentioned, which are used in very considerable numbers in the textile, electrical and other industries.

It will be understood that various changes and modifications may be made in the embodiments herein illustrated and described without departing from the scope of the invention as defined in the following claims.

Having thus described the invention, what is claimed as new and desired to be secured by Letters Patent is:

1. In a spool, in combination, a tubular barrel, a pair of end disks disposed in contact with either end of said barrel and each provided with a central aperture registering with the bore of said barrel, curved metallic securing elements of considerable arcuate extent disposed within said disk apertures and the ends of said barrel, each of said elements snugly contacting the periphery of one of said apertures and having a flange adapted to overlie and retain the margin of said aperture and another flange adapted to be embedded in the material of said barrel, said elements being of definite longitudinal cross-sectional configuration and of an original diameter smaller than the diameter of said apertures, and adapted to be moved radially into position during the application of said end disks without longitudinal distortion of said elements, and wooden plugs disposed with a driving fit within the ends of the bore of said barrel centrally of said securing elements.

2. In a spool, in combination, a barrel provided with a tubular opening in an end thereof, an end disk having a central aperture adapted to register with said opening, a split annulus expanded into said opening and aperture without longitudinal distortion for securing said disks to said barrel, a pair of spaced flanges formed on said annulus, one of said flanges, when the spool is assembled, overlying the margin of the aperture in said end disk and the other flange embedded in the material of said barrel within said tubular opening.

3. In a spool, in combination, a barrel provided with a tubular opening in an end thereof, an end disk having a central aperture adapted to register with said opening, a split annulus expanded into said opening and aperture without longitudinal distortion for securing said disks to said barrel, a pair of spaced radial projections formed on said annulus, one of said projections, when the spool is assembled, overlying the margin of the aperture in said end disk and the other embedded in the material of said barrel within said tubular opening.

50 In testimony whereof I hereunto affix my signature.

CHARLES K. DUNLAP.
